UNITED STATES PATENT OFFICE.

ALBERT H. MORI, OF BROOKLYN, NEW YORK.

FLOAT.

Application filed September 27, 1921. Serial No. 503,507.

To all whom it may concern:

Be it known that I, ALBERT H. MORI, a citizen of the United States, and resident of the borough of Brooklyn, county of Kings, city and State of New York, have invented certain new and useful Improvements in Floats, of which the following is a specification.

The invention relates to the production of floats having many advantageous qualities and particularly floats adapted for use in industrial appliances such, for example, as carbureters. My new float is suitable for advantageous use under atmospheric as well as increased pressures. Heretofore floats have generally been hollow since it was deemed essential for the purposes of achieving the necessary responsiveness to fluid level that without a hollow core or center a proper float could not be made. Where such floats were made of metal alone they were extremely expensive to construct. It has, therefore, been proposed to use a hollow core member of celluloid, or similar material, upon the surface of which an electrolytic deposit of metal is allowed to take place. This method of construction, although advantageous from many aspects, has not proven to be the final solution of the problem since floats thus made are necessarily to a certain extent fragile. There have, of course, also been wooden floats and probably also wooden floats encased in a metal shell, of which the former are objectionable because of susceptibility to fluid influences and the latter because too sluggish. Metal floats filled with cork have also been used but here again the necessity of a special manufacture of the metal casing renders such a float very expensive.

It has long been recognized that the ideal form of float would be one consisting of a metal shell that was capable of being constructed with the least possible expense and which instead of being hollow, would contain a filler completely occupying the interior of the metal shell without, however, to any substantial extent, decreasing floating sensitiveness of the metal shell. It was not, however, deemed possible to realize this condition because it was difficult to conceive how any such result could be achieved. I have now found that provided I employ certain particular and specific types of ligneous material and treat them in a certain way, I

am capable of producing the result that has thus far baffled the art.

I have discovered in that type of wood known as balsa wood, a material which is sufficiently low in specific gravity to offer little and practically no sensible obstruction within those limits of sensitiveness which are required for the purposes for which generally a hollow metal float is used. This material is capable of being turned or otherwise shaped to any desired configuration and when so shaped, to present a surface which is smooth and continuous as opposed, for example, to the irregular or recessed surface of cork or the like. The balsa wood, once it is properly shaped and smoothly surfaced, can readily be adapted to receive an electrolytic deposit of metal such as copper but being soft and porous this special wood, when placed in an electrolytic bath, is likely to absorb moisture and thereby not only become defective for the purposes for which I desire to use the same but also will gain in weight to such an extent as to render it more or less useless in connection with the construction of floats. I, consequently, after preparing the balsa wood as to shape and surface, treat it with a waterproofing material preferably of the type that is founded upon the use of a volatile liquid, such as dissolved cellulose or cellulosic material. The use of such waterproofing material does not affect the weight of the wood; and the vehicle for the waterproofing material, being volatile, does not remain in the wood or tend to penetrate it in any permanent fashion. Waxes or paraffins or other waterproofing material may also be used although they are less recommended. The waterproofed balsa wood can be immersed in an electrolytic bath without danger of penetration of the wood by the moisture contained in the bath and a deposit of copper can then readily be caused to be formed upon the waterproofed surface of the wood after the said surface has been treated in the usual way to adapt it for the reception of an electrolytic deposit. The metal deposited by electrolysis can be regulated with respect to any desired thickness of sheet or layer of enveloping metal. The accessories of a float can also be very easily dealt with since the wooden foundation affords an opportunity of using simple fastening appliances or methods. Thus if some particular float re-

quires the use of a central rod to be associated therewith, all I need to do is to sink the rod into the wood or by the use of a plate and screws to fasten the rod upon the wood and then by roughening the surface of the metallic components in the regions adjacent to the wood, adapting the whole device to be coated by a continuous layer of electrolytically-deposited metal.

10 A float made in accordance with my invention possesses the full requisite buoyancy and sensitiveness of a hollow metal float, is extremely inexpensive to manufacture and is really stronger and better than a hollow metal float because of the fact that the interior is not gaseous but is solid. Furthermore, by reason of the fact that the interior of my float is completely filled, slight mechanical jars or blows do not have to be absorbed by the metal alone but can be transmitted throughout the whole float, thereby avoiding, except in extreme cases, the formation of dents. Even where mechanical influences such as would make deep dents in a hollow metal float become operative on my float, the depression in the metal will be less accentuated and less likely to cause rupture of the metal shell. I have found that balsa wood offers considerable resistance to a blow, so that if a shell surrounding the balsa wood were subjected to a jar or a blow, the balsa wood would resist the tendency of the shell to be indented. This appears to be a peculiar characteristic of balsa wood, for it has not heretofore been known that there was any ligneous substance having a specific gravity of approximately cork and at the same time resisting a deformation change as much as some of the harder woods.

30 35 40 There are many other advantages which flow from procedure according to my invention.

The figure in the drawing is an eleva-

tion partly in section of the subject matter of the invention. In the drawing, *a* represents a float chamber of any usual type while *b* represents the means associated with the float chamber and subject to actuation according to the level of the fluid in the chamber so as to control operations outside of the float chamber; *c* is my new float shown as broken away at one point so as to exhibit interior construction, i. e., the balsa wood foundation *d*, the waterproofed surface thereof *e* and the electrolytically-deposited metal shell *f*.

55 What I claim is:

1. The combination of a float chamber, means associated therewith adapted to govern operations in accordance with conditions determined by the level of the fluid in said chamber, and a float member arranged to cause actuation of said means, said float member comprising a ligneous element possessing the characteristics of balsa wood and having approximately the density of cork 60 and the resistance to deformation of heavier woods, the ligneous element having a shell 65 covering the same and composed of an electrolytically deposited metal.

2. The combination of a wood foundation member and a metal shell thereon, said metal-coated wood adapted to serve as a float member and constituted, with respect to the wood foundation, of wood of the balsa type having approximately the density of cork and the resistance to deformation of woods heavier than cork and waterproofed 75 as to its surface, and, with respect to the metal shell, of an electrolytically-deposited sheet, deposited upon and in contact with 80 the waterproofed surface of the wood base.

70 75 80 In testimony whereof I have hereunto set my hand.

ALBERT H. MORI.
